UNITED STATES PATENT OFFICE.

ELISE E. MOSER, OF WATERTOWN, WISCONSIN.

DEVICE FOR FACILITATING THE REBUILDING OF FIRES.

SPECIFICATION forming part of Letters Patent No. 727,181, dated May 5, 1903.

Application filed July 29, 1902. Serial No. 117,553. (No model.)

To all whom it may concern:

Be it known that I, ELISE E. MOSER, a citizen of the United States, residing at Watertown, in the county of Jefferson and State of Wisconsin, have invented a new and useful Device for Facilitating the Rebuilding of Fires, of which the following is a specification.

My invention is an improved device for facilitating the rebuilding of fires; and the object thereof is to provide a portable contrivance by which the fire may be remade without the necessity of removing all of the unburned coals and ashes from the stove.

With the above object in view my invention comprises a plate of such shape and design that it may be readily inserted into the stove and easily pushed down through the coal and ashes to divide the fire-box into two compartments, from one of which the coal and the ashes are removed, as will be clearly set forth hereinafter. The said plate has a series of holes arranged therein and also a bail-handle, by which it may be easily and conveniently handled.

The invention also consists of certain details of construction and novelties of combination, as will be fully described hereinafter, reference being had to the drawings, in which—

Figure 1 is a perspective view of my improvement as applied to a magazine or self-feeding stove. Fig. 2 is a sectional view of the same, the line of the section being drawn directly below the magazine of the stove. Fig. 3 is a detail perspective view of my improvement, and Fig. 4 is a detail view illustrating a slightly-modified construction.

In the drawings I have shown my device as applied to an ordinary magazine-stove, for which it is especially designed; but I do not wish it understood that it is only applicable to such style of stove, as it may with equal effectiveness be used upon any and all kinds of stoves or furnaces.

By reference to the drawings it will be seen that I employ a plate A, which is bent substantially upon a compound-curved line through its entire length, with the sides A' extended forwardly, as clearly shown, so that when the plate is placed within the stove

the edges A' will contact with the fire-brick, as shown in Figs. 1 and 2 of the drawings. The body of the plate is perforated, as shown at A², any suitable number of holes being provided as may be found necessary, and upon the upper edge of the plate is secured a bail-shaped handle B, by which the plate may be easily and conveniently handled. In practice I permanently connect the handle to the plate; but, if desired, it may be made detachable, as shown in Fig. 4 of the drawings, so that it may be disconnected prior to starting the fire, and thus kept cool, so that it may be more easily handled.

The manner of using my improvement is as follows: If for any reason a fire should be allowed to go out and it is again found necessary to rebuild it, the plate is inserted into the stove through the door and pushed down through the coals in such position that the edges of the plate will rest against the fire-brick. The coals and ashes between the plate and fire-brick are then removed, leaving a space in which a fresh fire is started, the holes readily permitting sufficient draft and also allowing the heat and fire to escape through the coals that were left in the stove, and after a good fire has been built up the plate is withdrawn and the live coals contacting with the unburned ones will readily ignite them, thus providing a fire, and the necessity of removing the entire contents of the stove is avoided and the dust and labor caused thereby likewise avoided.

My invention will be found particularly advantageous for use in magazine or self-feeding stoves, and the plate forming, as it does, a partition in the fire-box will hold and prevent the coals within the magazine from falling.

It will be observed that by shaping the plate as described it will encircle the magazine for a slight distance, and the edges extending for some little distance past the magazine and upon either side thereof and curved outwardly, as described, a larger space is provided in which the fresh fire is built than if the plate were made straight.

It will be readily seen that I provide a very simple and efficient device that will be found most useful in restarting a fire.

Having thus fully described my invention,

what I claim as new, and desire to secure by Letters Patent, is—

A device of the kind described, comprising a plate having a series of perforations arranged therein, the body of the plate being arranged upon a compound-curved line throughout its entire length, and a handle connected

to the upper edge of the plate and upon either side thereof, substantially as shown and described.

ELISE E. MOSER.
